**OXYGENATED ORGANIC COMPOUNDS OF
IMPROVED ODOR**

Elaine Theodora Delaune and John Cecil Winkler, Baton Rouge, La., assignors to Esso Research and Engineering Company, a corporation of Delaware
No Drawing. Filed Mar. 26, 1962, Ser. No. 182,639
8 Claims. (Cl. 260—593)

The present invention relates to a method of improving the odor of contaminated oxygenated chemicals, especially lower molecular weight alcohols and ethers and the improved chemicals obtained by said method.

Most of the alcohols, ethers and ketones made by commercial methods have foreign odors which, depending on their strength and distastefulness, limit the end use of these oxygenated organic substances. For example, odor is an important characteristic in alcohols used in food, drugs and toilet articles. Likewise, ethers that might otherwise be utilized as anesthetics are frequently rejected on the basis of poor odor.

Considerable work has been carried out in the past in an attempt to make contaminated alcohols, ethers, etc. satisfactory for use in products wherein odor is a critical property. Fractional distillation methods have failed to accomplish the desired result because the odor-imparting contaminant is usually present in relatively small quantities and frequently boils in the same range as the oxygenated organic product. Efforts along other lines, such as the addition of potassium hydroxide, have similarly been unsuccessful in improving the odor quality of the above-mentioned chemicals.

It has now been discovered that trace amounts of certain phenolic compounds have a marked effect on the odor quality of biologically and synthetically prepared oxygenated products. One advantage of using small quantities of these additives is that they do not noticeably contaminate the product. For instance, when these additives are employed in concentrations of 1 or 2 p.p.m., the oxygenated chemicals will still pass the standard test methods used by the various industries; whereas other additives that have been experimented with heretofore, to be effective, must be used in such large amounts that they interfere with these tests.

The following is a structural formula which broadly defines the additives that come within the purview of the invention:

wherein R₃ and R₄ represent hydrogen or an alkyl radical, either straight or branched chain, containing 1 to 16 carbon atoms, preferably 1 to 5 carbon atoms, and R₁, R₂ and R₅ represent hydrogen or an organic radical, either cyclic, straight or branched chain, having 1 to 16 carbon atoms, preferably 4 to 10 carbon atoms, selected from the group consisting of alkyl and aroxy radicals; at least one of said R radicals represents an alkyl or aroxy group.

Among the phenolic compounds that can be used to improve the odor characteristic of organic oxygenated chemicals in accordance with the present invention are polyalkylated phenols such as

2,6-ditertiary-butyl para-cresol,
2,4-ditertiary-butyl phenol,
2-methyl-4-tertiary-butyl phenol,
2,6-dimethyl phenol, and

2

2,4-ditertiary-butyl-6-methyl phenol; and bis-phenol alkanes such as

4,4'-methylene-bis-(2,6-ditertiary butyl phenol),

2,2'-bis(p-hydroxyphenyl) propane,

4,4'-bis(2,6-ditertiary butyl phenol),

4,4'-methylene-bis-(6-tertiary-butyl-o-cresol) and

2,2'-methylene-bis-(4-methyl-6-tertiary-butylphenol).

It has been found that the most effective additives are those that possess a single phenol nucleus and have 2 or 3 straight or branched hydrocarbyl groups attached to the ortho, and/or para positions of the aromatic ring. Of the foregoing, the lower di- and tri-alkyl substituted phenol compounds are preferred. These compounds are represented by the following formula:

wherein R₆ is a lower alkyl group having 1 to 5 carbon atoms, and R₇ and R₈ are either hydrogen or lower alkyl groups having 1 to 5 carbon atoms. Usually one of the alkyl substituents is methyl and one or both of the others is tert-butyl. The other phenolic substances improve the odor of the product, but generally their effect is not as great.

30 In accordance with the present invention, a minute quantity of one or more of the organic additives is admixed with an oxygenated chemical having an undesirable alien odor. It is advisable to limit the concentration of additive to not more than about 10 p.p.m. (parts per million) in order to avoid further contamination of the product and possible interference with other tests which the chemical may have to pass in order to be suitable for a particular end use. It has been found that while as little as 0.01 p.p.m. (by wt.) has a beneficial result on the odor 35 quality of the substrate, best results are obtained when about 0.5 to 5 p.p.m. (by wt.) are employed. In the case of the para-cresol additives, it is usually not necessary to add more than about 1 or 2 p.p.m. in order to make the oxygenated product suitable for most purposes.

40 45 The odor improving agent can be contacted with the monohydric alcohol or other substance by simply mixing the two materials at room temperature. In some instances, it is advantageous to dissolve the additive in a portion of the liquid product in order to facilitate mixing and insure a homogeneous product.

50 55 Ambient temperature is eminently suitable for the addition of the agent to the contaminated product. However, higher and lower temperatures may be used. Broadly speaking, temperatures ranging from about 0° C. up to the boiling point of the oxygenated product can be employed with success. Pressure, of course, is not a critical condition and, therefore, for economic reasons, substantially atmospheric pressure should be used in the treatment of the oxygenated product.

60 65 The improvement in odor quality is almost instantaneous and remains for a considerable period of time. In fact, in the case of certain products, particularly isopropanol, even greater improvements are obtained by allowing the treated sample to age for several months at room temperature.

70 The oxygenated chemicals that can be improved by means of the present invention include primary and secondary alcohols, ethers and ketones. While the use of these additives has application to the higher molecular weight products, they find their greatest use in the treatment of substantially pure lower molecular weight substances such as ethanol, isopropanol and diethyl ether.

The oxygenated substances are generally aliphatic compounds that are either saturated or unsaturated and contain from 1 to 16 carbon atoms, preferably 2 to 4 carbon atoms, per molecule. Among the products that can be improved by the above-described treatment are water soluble primary, secondary and tertiary monohydric alcohols, such as methanol, ethanol, tertiary butanol, isopropanol and secondary butanol, derived from petroleum hydrocarbons; highly branched oxo alcohols such as decyl alcohol, hexadecyl alcohol and isooctyl alcohol; alkyl oxides such as diethyl ether, divinyl ether, methyl ethyl ether and diisopropyl ether; and ketones such as methyl ethyl ketone, methyl isobutyl ketone and acetone.

The phenolic additives will reduce or eliminate substantially all of the various types of extraneous odors commonly found in oxygenated organic products. For instance, in the case of alcohols made by hydrating olefins via the formation of sulfate esters, aldehyde, ketone, sulfur and butyl odors are frequently detected in the finished product. The hydrocarbyl-substituted cresol compounds are especially effective in the elimination of the aforementioned odors.

One method of evaluating the redolent property of a product is to prepare samples having graduated odor intensities that can be used to determine the strength of the odor in the oxygenated organic product. In one such method, the standard samples are assigned the values ranging from 1 to 12; the highest number representing the sample having the strongest odor. In this test, a rating of "6" is designated "acceptable." This does not mean that the product can be employed for all purposes since, obviously, some end uses require essentially odor-free materials. In such cases, the product cannot have a rating greater than "2" and preferably has a rating of "1." In other words, it must be substantially free of objectionable odors.

The following examples are given to provide a better understanding of the invention.

Example 1

In order to demonstrate the effectiveness of even trace amounts of the phenolic additives on the odor characteristic of alcohols, various samples of 95 vol. percent ethanol prepared by the hydration of ethylene obtained from a C₂ petroleum fraction, were treated with 1 p.p.m. of 2,6-ditertiary-butyl para-cresol. The cresol compound was dissolved in the alcohol samples with stirring at room temperature and atmospheric pressure. Then the samples were rated by a panel of three using the test method described above. None of the panelists knew which were the treated samples. The results are set forth in the table below.

EFFECT OF ADDING 1 P.P.M. OF 2,6-DITERTIARY-BUTYL PARA-CRESOL ON ODOR OF ETHANOL SAMPLES

Sample No.	1	2	3	4
	Rating			
Control	10A	12A	8R	12+R&A
Treated	3A	3A	2G	3A

A=aldehyde odor.
G=good-no significant foreign odor.
R=recycle sulfur odor.

The data in the above table show that in every case the odor of the ethanol samples treated with the cresol additive were "acceptable" and, in one instance the product had an odor quality that would be satisfactory for substantially all alcohol end uses. These results are far superior to the improvements obtained by other means used by the producers of synthetic ethanol. For example, it is unusual to find a commercial 95% ethanol that has an odor rating of less than 6.

Example 2

A sample of 95 vol. percent isopropanol having an odor rating of "8" was treated in the manner described in Example 1 with 1 p.p.m. of 2,6-ditertiary-butyl para-cresol. The treated sample had an odor rating of "6," thus making it acceptable for use in a number of products.

Example 3

A sample of diethyl ether prepared from ethylene was 10 treated in the manner described in Example 1 with 2 p.p.m. of 2,6-ditertiary-butyl para-cresol. The control sample had an odor rating of 8 HB (high boilers), while the treated ether had a rating of 3.

Example 4

Essentially pure methyl ethyl ketone having an odor rating of 12-A (sour odor) was mixed with 1 p.p.m. of 2,6-ditertiary-butyl para-cresol at room temperature, and its odor was thereby reduced to 6-A.

Example 5

A 95 vol. percent ethanol sample having an odor rating of 12-A was treated with 1 p.p.m. of 2,6-ditertiary-butyl para-cresol at room temperature. The treated ethanol 25 had an acceptable odor, and, furthermore, its permanganate time, which is a measure of the reducing substances present in the alcohol, was about the same as the control. However, when another sample of the same ethanol was treated with 10 p.p.m. of the para-cresol compound, the permanganate time decreased from about 30 minutes to 10 minutes. Thus, while 10 p.p.m. or more of these phenolic additives will improve the odor characteristic of the oxygenated products, large amounts 30 interfere with the permanganate time and other specification tests. It has been found that about 1 or 2 p.p.m. of these additives can be utilized without causing them to fail the other tests to which the products may be subjected. Larger amounts, i.e. up to about 10 p.p.m., of the phenolic compounds can be used where odor is the 35 only important characteristic.

Example 6

Sample #1 in Example 1 was treated with 3 p.p.m. of 4,4'-methylene-bis-(2,6-ditertiary butyl phenol) in 45 place of the para-cresol compound. The odor rating of the treated ethanol was improved to a 6-A class.

Example 7

A sample of diethyl ether having an odor rating of 50 8 HB was treated by dissolving 5 p.p.m. of 4,4'-methylene-bis(2,6-ditertiary butyl phenol) in it at room temperature and atmospheric pressure, and stirring the resulting mixture for about a minute. The treated product had a more acceptable odor, i.e. 4 HB.

Example 8

A sample of methyl ethyl ketone having an odor rating of 12-A (sour) was treated by dissolving 1 p.p.m. of 4,4'-methylene-bis(2,6-ditertiary butyl phenol) in it at room temperature and atmospheric pressure, and stirring the resulting mixture for 1 minute to insure a homogeneous solution. The treated product had a more acceptable odor rating of 8-A.

Example 9

A sample of tertiary butyl alcohol having an odor rating 12+ (sour) was treated by dissolving 1 p.p.m. of 2,6-ditertiary butyl p-cresol in it at room temperature and atmospheric pressure and stirring the resulting mixture for 1 minute. The treated product had an odor 70 rating of 10 (sour odor not present).

Example 10

Example 9 was repeated except 3 p.p.m. of 4,4'-methylene-bis(2,6-ditertiary butyl phenol) was used. The

treated tertiary butyl alcohol product had an odor rating of 10 (no sour odor present).

Example 11

A sample of secondary butyl alcohol having an odor rating of 12+ (heavy aldehyde-type odor) was treated by dissolving 5 p.p.m. 2,6-ditertiary butyl p-cresol in it at room temperature and atmospheric pressure and stirring the resulting mixture for 1 minute. The treated product had an odor rating of 10 (very little of the heavy aldehyde odor remained).

Example 12

A sample of acetone having an odor rating of 12+A is treated by dissolving 8 p.p.m. of 4,4'-methylene-bis (2,6-ditertiary butyl phenol) in it at room temperature and atmospheric pressure and stirring resulting mixture for 1 minute. The treated product had a more acceptable odor, i.e. 10-A.

Example 13

Example 12 was repeated except 3 p.p.m. of 2,6-ditertiary butyl p-cresol was used. The treated product had a more acceptable odor, i.e. 10-A.

Example 14

A sample of 95 vol. percent ethanol, having a disagreeable odor, is treated at room temperature by mixing it with 10 p.p.m. of 2-methyl-4-tertiary butyl phenol. Its odor is substantially improved.

Example 15

Similar results to those described in Example 14 are gotten when odorous ethanol is mixed with 10 p.p.m. of 2,6-dimethyl phenol.

Example 16

A sample of vinyl ether having a disagreeable hydrocarbon odor was mixed with 50 p.p.m. (wt.) of 2,6-ditertiary butyl-p-cresol and it was noted that the odor was much less after the addition of the cresol compound.

It is not intended to restrict the invention to the foregoing examples which are given merely to demonstrate some of the embodiments of the invention. It should only be limited by the appended claims in which it is intended to claim all the novelty inherent in the invention, as well as all of the modifications and equivalents coming within the scope and spirit of the discovery.

What is claimed is:

1. A composition of matter comprising an oxygenated organic liquid selected from the group consisting of 50 methanol, ethanol, tertiary butanol, isopropanol, secondary butanol, branched oxo alcohols having 1 to 16 carbon atoms per molecule, diethyl ether, methyl ethyl ether, diisopropyl ether, methyl ethyl ketone, methyl isobutyl

5 ketone, and acetone having dissolved therein 0.5 to 5 p.p.m. of an alkyl-substituted phenol compound having the structural formula

10 wherein R₆ is a C₁ to C₅ alkyl group and R₇ and R₈ are selected from the group consisting of hydrogen and C₁ to C₅ alkyl groups.

15 2. A composition matter as defined in claim 1 in which the alkyl-substituted phenol compound is 2,6-ditertiary butyl cresol.

20 3. A composition of matter as defined in claim 1 in which the oxygenated organic liquid is isopropanol and the alkyl-substituted phenol compound is 2,6-ditertiary butyl cresol.

25 4. A composition of matter as defined in claim 1 in which the oxygenated organic liquid is diethyl ether and the alkyl-substituted phenol compound is 2,6-ditertiary butyl cresol.

5. A composition of matter as defined in claim 1 in which the oxygenated organic liquid is methyl ethyl ketone and the alkyl-substituted phenol compound is 2,6-ditertiary butyl cresol.

30 6. A composition of matter as defined in claim 1 in which the oxygenated organic liquid is tertiary butyl alcohol and the alkyl-substituted phenol compound is 2,6-ditertiary butyl cresol.

35 7. A composition of matter as defined in claim 1 in which the oxygenated organic liquid is secondary butyl alcohol and the alkyl-substituted phenol compound is 2,6-ditertiary butyl cresol.

8. A composition of matter comprising ethanol containing a trace amount, not exceeding about 2 p.p.m., of 40 2,6-ditertiary-butyl para-cresol.
